UNITED STATES PATENT OFFICE.

JAMES HARRY SEEK, OF CHICAGO, ILLINOIS.

AUTOMATIC-ADJUSTING CARBURETER.

1,296,705.

Specification of Letters Patent. Patented Mar. 11, 1919.

Application filed December 4, 1912. Serial No. 734,992.

To all whom it may concern:

Be it known that I, JAMES HARRY SEEK, a citizen of the United States of America, and resident of Chicago, Cook county, Illinois, have invented a certain new and useful Improvement in Automatic-Adjusting Carbureters, of which the following is a specification.

My invention relates to an automatic adjusting carbureter—that is, a carbureter in which the supply of air or gasoline to the same is automatically regulated so as to comply with surrounding conditions. It is well known that when the engine is starting—that is, when it is cold—it is necessary that the supply of air to the carbureter be decreased or the supply of gasoline correspondingly increased in order to obtain the best carburetion. As the engine speeds up and thus warms up, it is necessary to then increase the supply of air. It has accordingly been difficult to obtain an adjustment of the carbureter which would give good carburetion both when the engine is cold and after the engine is heated up.

My invention, therefore, relates to an attachment by which the air passage is automatically controlled so that this air passage is substantially closed when the engine is cold—that is, on the condition of starting—and then when the engine heats up, this passage is opened and the valve controlling the passage is placed under the control of the ordinary valve adjusting spring.

My invention is likewise adaptable for adjusting the carbureter according to varying atmospheric pressures—that is, it can be adapted to vary the air supply according to the altitude at which the engine is operating, and is thus very useful in connection with aeroplanes in which difficulty is found in obtaining proper carburetion, as the pressure of the air varies with the change of altitudes.

My invention will be more readily understood by reference to the accompanying drawings in which I have illustrated certain embodiments of my invention. In these drawings—

Figure 1 represents a side elevation partly in section of a carbureter embodying the features of my invention.

Fig. 2 is a sectional view on the line 2—2 in Fig. 1.

Fig. 3 is a detail sectional view.

Fig. 4 is a side elevation partly in section

of a carbureter embodying a different specific embodiment of my invention.

Fig. 5 is a further modification, showing an electric attachment for operating an auxiliary valve.

Fig. 6 is a side elevation, partly in section, of a further modification.

Fig. 7 is a sectional view on the line 7—7 in Fig. 6.

Fig. 8 is a partly sectional side elevation showing a portion of an engine equipped with this invention, section being made axially with respect to one cylinder of the engine and with respect to the carbureter 70 nozzle.

I have not represented in detail any specific construction of carbureter, as my invention is capable of attachment to any standard form of carbureter.

I have accordingly represented in Fig. 1, a carbureter 11 to which there is connected an air supply passage 12, and which has the usual oil supply nozzle, 11^a, discharging in the mixing duct, 11^b. In this air supply passage there is a valve 13 which is held upon its seat 14 with a variable pressure by means of the adjusting spring 15. This adjusting spring is of the usual well known construction and forms no part of my present invention. Of course, it is understood that other forms of adjusting springs could be employed equally as well, as these springs are well known in the art. Mounted below the valve 13 there is a spider 16, which carries a stub 16^a, to which is secured one end of a helical spring 17. The opposite end of this spring is connected to the upper end of a plunger 18 which carries a spider 19. This spider is provided with a plurality of openings 20 in its lower side and with a circumferential flange 21, which flange normally closes the openings 22 in the valve casing 23. These openings 22 are triangular shaped, as shown in detail in Fig. 3, so that as this spider is raised these openings are gradually opened to admit the air through the same and thence through the openings 20 to the valve 13, from whence it can pass through the carbureter, provided this valve 13 is open.

The plunger 18 fits within a tube 24 which is connected at its lower end to a bulb 25. This bulb is filled with mercury, which mercury rises part way into the tube 24. This bulb is placed within a casting 26, which is connected to the pipe 27, which

pipe is either a hot water pipe from the pump on the water circulation or is the exhaust of the engine or any pipe whereby the heat of the engine will influence the mercury 5 in the bulb 25; or this bulb could be placed directly in the water jacket of the engine, if such is provided. With this construction, when the engine is cold, or that is when the same is starting, the mercury is 10 low enough in the tube 24 so that the spring 17 forces the plunger 18 down to the position shown in Fig. 1 whereby the air passage to the valve 13 is closed. This enables a better mixture to be obtained for 15 starting the engine. As the engine warms up, and it is then desired to increase the air supply, the mercury in the bulb 25 and tube 24 expands and forces the plunger 18 upward, thereby opening the passages 22 and 20 thus permits the air to pass through the openings 22 and thence through the openings 20 to the valve 13, which valve is under the control of the adjusting spring 15, in the usual manner.

25 In Fig. 4 I have shown, in place of the mercury column, a casting 28 secured to the pipe 27, which casting is hollow so as to provide a chamber 29 which is filled with an expansible gas. This chamber is closed 30 by a diaphragm 30, and the expansion of the gas as the engine warms up moves this diaphragm so as to operate the rod 31, which operates to take the tension off the spring 32, which spring normally holds the 35 valve 13 closed. The valve 13 is then placed under the control of the adjusting spring 15, in the same manner as hereinbefore described. There is likewise shown in this construction a second or heavier adjusting 40 spring 15^a which spring does not come into play until the valve 13 has been raised a short distance—say about one-eighth of an inch. This use of the light and heavier adjusting springs is well known in the art 45 and does not need further explanation.

Fig. 5 shows a further modification in which the mercury bulb 25 and tube 24 are retained, but this mercury, instead of operating directly upon the plunger, merely 50 closes an electrical circuit by means of contacts 33, 34, which operate to close the circuit of an electromagnet 35 through a battery or other source of current 36. This magnet upon energizing draws up its 55 plunger 37, to which is attached an arm 38 which operates a valve 39 in the air passage 40. A spring 41 is provided for normally holding the plunger 37 downward so as to maintain this valve 39 closed. With 60 this form of the invention, when the engine is cold—that is, starting—the valve 39 is maintained closed. As the engine heats up, the mercury rises in the tube 24 and closes the contact 34 which then causes the 65 electro-magnet 35 to energize to pull up its

plunger and rotate the valve 39 to open the same, whereby the air is permitted to pass through the passage 40 to the valve 13 which is under the control of the spring 15, in the usual manner.

In Figs. 6 and 7, I have shown a further modification, similar to the construction shown in Fig. 4 except that in place of the chamber containing the expansible gas, I employ the mercury column which operates 70 directly upon the plunger 41 the upper end of which is secured to the lever 42 which is held in its lowermost position by means of the spring 43. As the engine heats up the mercury rises and forces the plunger 80 upward which thus relieves the tension on the spring 43. This spring 43 normally tends to maintain this valve 13 closed, but when the tension is removed from the same, in the manner described, the valve is then 85 placed under the control of the adjusting springs 15 and 15^a, in the manner described in connection with Fig. 4.

While I have illustrated certain modifications of my invention, it is understood 90 that I do not wish to be limited to the exact construction shown and described, as other means can be employed and still carry out the purpose of my invention. I, however, believe that I am the first to provide 95 an automatic adjustable carburetor whereby this carburetor is adjusted automatically either by variation of the temperature or air pressure.

What I claim as my invention is: 100

1. In an internal combustion engine, in combination with the combustion or explosion chamber, a carburetor, means controlling the entrance of air into the carburetor, and a thermostatic device positioned to be 105 influenced by changes of temperature of the combustion chamber operatively connected with said air-inlet-controlling means for increasing the air inlet as the temperature increases.

2. In an internal combustion engine, in combination with the water jacket, a carburetor having an air inlet and means for controlling the same; a thermostatic device positioned to be influenced by changes of 115 temperature of the cooling water of the water jacket, and connections by which the said thermostatic device operates the air-inlet-control of the carburetor for increasing the air admitted upon increase of temperature of the cooling water.

3. In an internal combustion engine, in combination with the explosion or combustion chamber of the engine, a carburetor which supplies motive fluid to the engine 125 having an air inlet; a valve for controlling said inlet; a thermostatic device positioned to be influenced by the changes of temperature of the combustion chamber, and connections from said thermostatic device for op- 130

erating the valve to increase and diminish its opening upon an increase and diminution of temperature respectively.

4. In an internal combustion engine, a carbureter, an air passage for admitting air to the interior of said carbureter, a valve in this passage, a spring for adjusting the tension on this valve, and temperature-controlled means located outside of the carbureter for further controlling the operation of said valve.

5. In an internal combustion engine, a carbureter, an air passage for admitting air to the interior of said carbureter, a valve in this passage, a spring for adjusting the tension on this valve, a water jacket for said engine, and thermostatic means controlled by the temperature of said water jacket for further controlling the operation of said valve.

20 6. In an internal combustion engine, in combination with the combustion chamber, a carbureter through which motive fluid is supplied to the combustion chamber, said carbureter having an air inlet; a valve which 25 controls said inlet; means for yieldingly resisting the opening of the valve adapted to cause the valve to open more or less widely according to the suction of the engine thereon; a thermostatic device located subject to 30 the influence of change of temperature of the combustion chamber, and yielding connections between said thermostatic device and said valve adapted to increase and decrease the yielding resistance to the opening 35 of the valve upon decrease and increase of

the temperature affecting the thermostatic device.

7. In an internal combustion engine, in combination with the water jacket, a carbureter which supplies motive fluid having an 40 air inlet; a valve to control said inlet; a spring which yieldingly resists the opening of the valve; a thermostatic device controlled by the temperature of the water jacket, and connections from said thermostatic device for further modifying the operation of the valve.

8. In a device of the character set forth, the combination of a mixing duct, a liquid fuel jet nozzle arranged to discharge in said 50 duct, means for supplying air to said duct, and thermostatic means operative through engine temperature and adapted to increase the supply of air relative to the liquid fuel supplied to the mixing duct, as such temperature increases.

9. In a device of the character set forth, the combination of a mixing duct, a liquid fuel supply arranged to discharge into said 55 duct, means for supplying air to said duct, and thermostatic means operative through engine temperature to automatically vary the proportions between the air and the liquid fuel supplied to said duct.

Signed by me at Chicago, Illinois, this 65
18th day of November 1912.

JAMES HARRY SEEK.
